[57] CLAIM

The ornamental design for a physical exerciser, substantially as shown and described.

DESCRIPTION

FIG. 1 is a top plan view of a physical exerciser showing our new design;
FIG. 2 is a right side elevational view thereof, the side opposite being substantially a mirror image;
FIG. 3 is a bottom plan view thereof;
FIG. 4 is a front elevational view thereof; and,
FIG. 5 is a rear elevational view thereof.

FIG. 1

FIG. 2

FIG. 3

FIG. 4
